UNITED STATES PATENT OFFICE.

HARRY H. HOLLAND AND JASON C. STEARNS, OF WORCESTER, MASSACHUSETTS; SAID HOLLAND ASSIGNOR TO SAID STEARNS.

FOCUSING DEVICE FOR ELECTRIC LAMPS.

1,137,322.

Specification of Letters Patent.

Patented Apr. 27, 1915.

Application filed August 22, 1914. Serial No. 857,997.

To all whom it may concern:

Be it known that we, HARRY H. HOLLAND and JASON C. STEARNS, citizens of the United States, residing at Worcester, in the county 5 of Worcester and State of Massachusetts, have invented a new and useful Focusing Device for Electric Lamps, of which the following is a specification.

This invention relates to a construction 10 of lamp socket by which the turning of the lamp will move it longitudinally and thus focus it with respect to the stationary mirror with which the lamp is used.

The principal objects of the invention are 15 to simplify the arrangement for accomplishing this result so as to reduce the number of pieces employed and cheapen the construction and assemblage of the parts.

Reference is to be had to the accompanying 20 drawings in which, Figure 1 is an elevation of a lamp socket constructed in accordance with this invention; Fig. 2 is a similar view of the opposite side thereof with parts broken away to show interior 25 construction; Fig. 3 is an elevation of a modification; and Fig. 4 is a view of the other side of the same with parts broken away to show interior construction.

In the form shown in Figs. 1 and 2, the 30 outer sleeve 10 is provided with a projection 11 surrounding it, against which the mirror 12 is held. These parts are intended to be fixed in the lamp casing so that they are stationary. The sleeve is provided with 35 a helical slot 13 on one side and with a spring tongue 14 on the other. This tongue is formed simply by slitting the metal longitudinally at two separated points, the tongue coming between them. The tongue 40 is corrugated on both surfaces.

Inside the sleeve is a cylindrical bushing 16 for receiving the hard rubber plug 17. Inside the plug is a screw threaded rod 18 which has a terminal 19 for the wire. A 45 spring 20 entering a socket in the plug 17 presses against a slotted head 21 on the rod and firmly forces this out toward the lamp 22 which is designed to be inserted in the end of this bushing in the usual way and 50 have its terminal engage a metallic projection extending inwardly from the head 21.

The bushing 16 is formed from a section of comparatively thin metal tubing and has a helically arranged series of corrugations

upon its outer surface as clearly shown in 55 Fig. 1.

The bushing 16 is also provided with a lug 23 integral therewith or secured thereto, said lug being adapted to enter and co-operate with the helical slot 13 to relatively 60 position the sleeve 10 and bushing 16 longitudinally.

The slit at the left hand side of the tongue 14 is extended obliquely downwardly so as to permit that portion of the sleeve 10 65 which borders the upper end of the slot 13 to be sprung outwardly to permit the lug 23 to be inserted in the slot 13.

In operation it will be understood that the sleeve 10 is held in stationary position 70 in the lamp frame and that the lamp itself is introduced into the end of the bushing in the usual way. The turning of the lamp results in moving the lug 23 along the slot 75 13 and consequently moving the lamp longitudinally, and at the same time the tongue engages the corrugated surface of the bushing 16 and serves as a ratchet to hold the lamp in any adjusted position.

In the form shown in Figs. 3 and 4, similar 80 results are secured, but the mechanism is not so simple to make and assemble. In this case there is an outer sleeve 30 having a surrounding projection 31 at one end for the mirror. This sleeve is provided with a 85 helical groove 33. It is also provided with a longitudinal groove 34. Inside the sleeve is a bushing 36 for receiving the insulating plug 37 and this has a conducting rod there- 90 in connected with the terminal 39 in a manner similar to that shown in Fig. 2. The ring 44 has a projection 38 for guiding it along the slot 34.

The lamp is held in the end of the bushing 95 in the same way as shown in Fig. 2. On the outside of the hard rubber insulating plug 37 is fixed a ring 40 having ratchet teeth on one flat surface thereof. This ring is provided with a screw 43 entering the slot 33 100 so that the turning of the lamp will result in moving it longitudinally, as in the other case. The second member of the ratchet device comprises a second ring 44 having teeth adapted to engage the teeth of the ring 40, and a spring 45 is provided between this 105 ring and the edge of the projection 31 so as to hold the ratchet members together. The operation of the adjustment will be obvious.

Although we have shown and described only two forms of the invention, we are aware of the fact that other modifications can be made by any person skilled in the art without departing from the scope of the invention as expressed by the claims. Therefore, we do not wish to be limited to the particular constructions shown, but—

What we do claim is,—

- 10 1. In an adjusting and focusing device for an electric lamp, the combination of a cylindrical sleeve having a helical groove therein, a bushing inside the sleeve adapted to move therein, said bushing having a circumferential ratchet thereon, a projection extending from said bushing into said slot, whereby the turning of the bushing will move the same longitudinally, and a second ratchet member engaging the ratchet member of the bushing and connected with the sleeve.
- 15
- 20

2. In a focusing and adjusting device for an electric lamp, the combination of a sleeve having a helical slot in the cylindrical portion thereof, and a bushing movable therein provided with longitudinal external corrugations thereon and having a projection extending into said slot for causing the bushing to move longitudinally when turned, said sleeve being provided with a resilient tongue having longitudinal corrugations thereon for engaging the corrugated surface of the bushing and constituting a ratchet.

In testimony whereof we have hereunto set our hands, in the presence of two subscribing witnesses.

HARRY H. HOLLAND.
JASON C. STEARNS.
